UNITED STATES PATENT OFFICE.

GEORGE SCHULER, OF WOODSIDE, NEW YORK.

SNOW GATHERING AND MELTING MACHINE.

1,106,735.

Specification of Letters Patent. Patented Aug. 11, 1914.

Application filed December 7, 1912. Serial No. 735,380.

To all whom it may concern:

Be it known that I, GEORGE SCHULER, a subject of the Emperor of Germany, residing at Woodside, Queens county, State of New York, have invented certain new and useful Improvements in Snow Gathering and Melting Machines, of which the following is a full, clear, and exact description.

This invention relates to an improvement 10 in snow-removing devices and relates more particularly to a form of plow designed to collect snow from a street, for instance, and melt the same, finally disposing of the melted snow or water.

15 My invention comprises the combinations and arrangement of parts and details of improvement which will be hereinafter more fully set forth.

I will now proceed to describe my invention in detail, the novel features of which I 20 will point out in the appended claims, reference being had to the accompanying drawings, forming part hereof, wherein:—

Figure 1 is a longitudinal sectional view 25 of a portion of a truck and my improved attached snow-gathering and melting machine. Fig. 2. is a plan view thereof; Fig. 3 is an enlarged cross-sectional view, the section being taken on a line 3—3 in Fig. 1, certain 30 parts being omitted; Fig. 4. is an enlarged sectional detail view of one of the elements of the conveyer and melter; Fig. 5. is an enlarged fragmentary plan view of the conveyer cylinder; Fig. 6. is an enlarged 35 sectional view of the rear end of the conveyer cylinder, and Fig. 7. is an end view thereof.

As herein illustrated my improved snow-gathering and melting device is located in front of a truck or wagon comprising a body 40 1 and wheels 2, one pair only being shown. In this instance the body 1 of the truck is carried by frames 3 upon which the snow-gathering and melting device 4 is mounted.

As herein embodied, my improvement 45 comprises a plurality of hot water generators or heaters 5 and 6, which are located within a jacket 7 (Fig. 3). Under the generators is mounted a collecting cylinder 8 within which I rotatably mount a conveyer 9 consisting of a plurality of radially disposed perforated pipes 10 carried by a rotatable hollow shaft 11 (see Fig. 4). At one 50 end the shaft 11 is carried by a support 12 and at the other end thereof by a perforated 55 plate 13. To convey hot water from the

generators 5 and 6, I provide a header 14 to which are connected manifold pipes 15, each of which is connected to its respective generator by risers 16, each riser being provided with a valve 17. The duct 18 conveys 60 the hot water from the header 14 to the hollow shaft 11. To generate the hot water, I provide gas-burners 19 consisting of perforated pipes which lead from headers 20 which in turn are connected to a manifold 65 21 by nipples 22 containing valves 23. The manifold 21 is connected to a fuel supply tank 24 by a pipe line 25 containing a valve 26'. The tank 24 is designed to retain gasoline or any other liquid or gaseous fuel. To 70 provide a blast or flame jet I force air into the tank 24 by means of a blower 26 through a pipe 27. The blower 26 is operated by a motor 28 by means of a belt 29. When air is forced into the fuel tank it will become 75 impregnated by the combustible liquid or gas and will burn at the perforations in the burners 19. As can be seen in Fig. 3, the generators 6 are larger than the generators 5 for the reason that I am able to place more 80 burners around the middle generators, and consequently more water can be heated than in the side generators, which are heated only at one side, and the bottom, instead of both sides and bottom.

To gather up the snow I provide one end 85 of the collecting cylinder 8 with a scoop 30 and an advancing mechanism 31 comprising a belt 32 and paddles 33 carried thereby. The belt 32 is operated by pulleys 34, one 90 of which is rotated by means of a sprocket gearing comprising a chain 35 and gears 36. The forward gear 36 is carried by a shaft operated by a gear 37 meshing with a gear 38 on the shaft 39. The shaft 39 carries on the end thereof a gear 40 meshing with a gear 41 on the lower end of a shaft carrying a gear 42 meshing with a gear 43 carried by the shaft of the motor 28. The function of the motor 28 is to drive the air pump 26 100 and conveyer 9.

As the machine is propelled forward, the scoop 30 will gather up the snow and the advancing device 31 will force the gathered snow into the cylinder 8, at which time it 105 will encounter the conveyer 9 and be propelled toward the perforated plate 13. During the rotation of the conveyer, hot water will be emitted through the perforations in the conveyer elements 10 and will mix with 110

the snow and melt the same. The function of the perforated plate 13 is to prevent slush or partly melted snow from passing out of the cylinder 8 to the ground. As the plate 5 13 is perforated, nothing but water will pass out of the cylinder, and as the snow is stirred up by the conveyer it will be rapidly melted by the hot water.

To keep the generators filled with water, 10 I preferably pump some of the melted snow-water back into the said generators. To collect some of the water, I provide the cylinder 8 with a well 44, in which the water will settle. To return or introduce the water into 15 the generators I provide a pump 45 which is operated by the motor 28. The suction side of the pump is connected with the well 44 by a suction pipe 46. The delivery side of the pump is connected to the generators by a delivery pipe 47. The pipe 47 delivers the water to a manifold 48 which in turn is connected to the generators by valve-controlled nipples 49.

As can be seen in Figs. 1 and 6, the rear 25 end of the cylinder 8 is provided with a pivotally mounted wing plate or apron 50 which is provided with a threaded saddle 51 adapted to receive the threaded coupling 52 of a hose 53. The apron 50 carries a 30 bracket 54 through which a pin can pass into openings in one side or wing 55 of the cylinder 8. The function of the bracket 54, pin and openings is to hold the apron down as in Fig. 1 or up as in Fig. 7. When the 35 apron is down the melted snow will flow into the street, thence to the gutter, if the street is level. Should the machine be operating on a hill, the apron would be raised, as in Fig. 3, and the hose 53 connected as shown 40 through which the melted snow-water can flow to the gutter or any other suitable place. If desirable, the water can be collected in barrels or tanks. As can be seen in Fig. 1 the forward belt-wheel 34 is carried 45 by pivotal brackets 56 which are adjustable so that the forward end of the snow-advancing device or propeller 31 can be raised or lowered to accommodate the device to the depth of the snow. The nearer the said forward 50 end of the propelling device 31 is to the scoop, the more snow will be delivered to the cylinder 8.

A further feature of my improvement is a 55 sweeper 57 which is adapted to be adjusted to any angle relative to the axis of the conveyer 8. The sweeper 57 is carried by a frame 58 pivotally mounted in a bearing on the body of the truck.

In order that I can convey hot water directly to the cylinder or chamber 8 I provide 60 by-pass pipes 76 containing valves 77. The hot water so conveyed can be used to melt the snow independently of the heated conveyer or in conjunction therewith. A valve 65 78 in the pipe or duct 18 closes the said pipe

should I desire to use only the hot water from the pipes 76. To prevent the melted snow in the chamber 8 from running into the scoop when the machine is operating on a down grade, I provide a baffle plate 79 which extends across the mouth of the cylinder (see Fig. 1). To keep the scoop in contact with the ground I provide a spring 80 (Fig. 1). If desirable the rear end of the scoop 30, and advancing device 31 may 75 be located in alinement with the axis of the conveyer 9 instead of at the bottom of the receiving chamber 8, as shown.

Having now described my invention, what I claim and desire to secure by Letters Patent is:

1. A snow remover comprising a conveyer including a hollow shaft, radially disposed tubes in communication with and carried by the shaft, said tubes being arranged in helical formation and in relatively adjacent contacts, hot water generators, and means for conducting the hot water from the generators to the conveyer.

2. A snow remover comprising a receiving chamber provided with a well, a hollow conveyer within said chamber, means for generating hot water, means for conveying water from the generator to the conveyer, a pump, a pipe connecting said well and 95 pump, and a pipe connecting said pump and generator.

3. A snow remover comprising a receiving chamber, provided at one end thereof with a pivotal apron, means carried by the apron to receive a hose, a hollow conveyer within said chamber, hot water generators, and means for conveying water from said generators to the conveyer.

4. A snow remover comprising a conveyer 105 composed of a plurality of perforated pipes arranged in helical formation and in contact with each other, and means for introducing hot water into said conveyer.

5. A snow remover comprising a conveyer 110 composed of a plurality of perforated pipes arranged in helical formation and in contact with each other, a hot water generator, and means for introducing the water from said generator into said conveyer.

6. A snow remover comprising a conveyer including a hollow shaft, a plurality of perforated radially disposed pipes in communication with the shaft and arranged in helical formation and in contact with each other, 120 and means for introducing hot water into said conveyer.

7. A snow remover including a receiving chamber, a combined conveyer and heater operative in said chamber, an apron pivotally connected to the outlet from the chamber, means for securing the apron in different positions with relation to the chamber, and a hose connection carried by the apron.

8. A snow remover including a receiving

chamber, a combined conveyer and heater operative in said chamber, an apron pivotally connected to the outlet from the chamber, means for securing the apron in different positions with relation to the chamber, a hose connection carried by the apron, a perforated disk arranged in the chamber intermediate the conveyer and apron.

9. A snow remover including a receiving chamber, a spiral conveyer operative therein, means for introducing a heating medium within the spiral conveyer, a perforated head closing the chamber beyond the conveyer, a well supported by the chamber beyond the head, and means operative in the

well for delivering water therefrom to the generators.

10. A conveyer and melter for snow removers including a hollow shaft, a plurality of perforated pipes projected radially of 20 the shaft and in communication therewith, said pipes being in contact with each other radially of the shaft and disposed in helical formation longitudinally thereof.

Signed at New York city, N. Y., this 6th 25 day of December, 1912.

GEORGE SCHULER.
